UNITED STATES PATENT OFFICE.

BEN HOLTER, OF WHITEFISH, MONTANA.

RIFLE-BARREL.

1,230,712.

Specification of Letters Patent. Patented June 19, 1917.

Application filed January 3, 1917. Serial No. 140,371.

To all whom it may concern:

Be it known that I, BEN HOLTER, a citizen of the United States, and a resident of Whitefish, in the county of Flathead and 5 State of Montana, have invented a new and Improved Rifle-Barrel, of which the following is a full, clear, and exact description.

The object of the invention is to provide a new and improved rifle barrel arranged 10 to insure the long life of the barrel, to increase the velocity of the projectile, and to insure accurate flight thereof in comparison to a like projectile fired from a barrel of usual construction.

15 In order to accomplish the desired result, the wall of the bore of the barrel is made polygonal in cross section.

A practical embodiment of the invention is represented in the accompanying drawings 20 forming a part of this specification in which similar characters of reference indicate corresponding parts in all the views.

Figure 1 is a perspective view of the muzzle end of the rifle barrel;

25 Fig. 2 is a longitudinal central section of the same;

Fig. 3 is an enlarged end view of the same; and

Fig. 4 is a similar view of a modified form 30 of the same.

The barrel 10 is provided with a bore 11, the wall of which is made in cross section in the form of a polygon, which may be a regular one; for instance, as shown in Fig. 35 3, a nine-sided polygon, or an irregular one with alternating long and short sides, as illustrated in Fig. 4. In this case each short side is approximately one-third the length of an adjacent long side.

40 In making the bore, the sides of the polygonal walls are given a rapid twist in excess of that usually found in the bore of rifle barrels as now generally constructed. By constructing the rifle barrel in the manner 45 described the long life of the barrel is insured owing to the fact that there are no projecting lands to wear away, and the occlusion of the gases generated by the explo-

sion of the powder is complete thus eliminating a trouble that usually arises from the 50 erosion of the interior surface of barrels as now constructed and which erosion is commonly called "gas cutting." It will also be noticed that by the construction described and shown sharp angles between the lands 55 and grooves, such as are generally found in barrels as heretofore constructed, are eliminated and hence the bore can be readily cleaned. Owing to the lessened mechanical friction of the passage of the bullet or projectile through the bore the defect known as 60 "metal fouling" is eliminated, that is, the disposition of metal from the bullet or projectile on the surface of the bore is entirely avoided. A rifle barrel made according to 65 the improvement described provides a more regular and accurate course of flight of the projectile than is possible with rifle barrels as heretofore constructed especially as the projectile is not liable to deformation and is 70 built at the muzzle in cylindrical form. It 75 will further be noticed that the complete occlusion resulting from the explosion preserves the form and smoothness of the wall of the bore and also prevents the erosion of 80 the surface of the projectile itself thus permitting it to leave the muzzle without having its axis deflected by the blast of the gas escaping alongside it. Owing to the elimination of metal fouling and extreme deformation of the projectile it is possible to give 85 the projectile a considerably increased rate of rotation over that which is now considered practical, and hence a rapid twist of the sides of the bore may be safely used. On account of the increased rate of rotation 90 of the projectile a great increase of gyroscopic stability is obtained. As there are no sharp angles or crevices in the bore it offers no place for the impaction of powder residue and fragments of metal liable to be 95 welded fast to the inner face of the barrel by the heat and pressure of succeeding discharges. It is understood that the number of the sides of the bore may be varied to suit the caliber and the projectile to be used

for any rifle barrel, and hence I do not limit myself to the number of sides shown in Figs. 3 and 4.

Having thus described my invention, I claim as new and desire to secure by Letters Patent:—

1. A rifle barrel having the wall of its bore composed of alternating relatively nar-

row and wide lands forming an irregular polygon each of said lands having a rapid 10 twist.

2. A rifle barrel having the wall of its bore composed of alternating relatively narrow and wide lands forming an irregular polygon.

BEN HOLTER.
